(57) **CLAIM**

The ornamental design for a cushion as shown and described.

DESCRIPTION

FIG. 1 is a top perspective view of a cushion, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a cross-sectional view taken through line 9-9 of FIG. 7 thereof;

FIG. 10 is a cross-sectional view taken through line 10-10 of FIG. 7 thereof;

FIG. 11 is a cross-sectional view taken through line 11-11 of FIG. 7 thereof; and,

FIG. 12 is a cross-sectional view taken through line 12-12 of FIG. 7 thereof.

1 Claim, 8 Drawing Sheets(56)
